(21) Appl. No.: **29/230,488**

(57) **CLAIM**

(22) Filed: **May 23, 2005**

The ornamental design for a frequency measuring device for a crystal resonator, as shown and described.

(30) **Foreign Application Priority Data**

DESCRIPTION

Nov. 24, 2004 (JP) 2004-035789

FIG. 1 is a perspective view of a frequency measuring device for a crystal resonator of a new design;

(51) **LOC (8) Cl.** 10-04

FIG. 2 is a perspective view thereof wherein a cover is open;

(52) **U.S. Cl.** D10/46

FIG. 3 is a rear elevational view thereof;

(58) **Field of Classification Search** D10/46; 73/24.06, 580, 778; 310/8.2, 8.9, 320, 344, 310/353, 361, 370; 324/715-719; 333/72

FIG. 4 is a top plan view thereof;

See application file for complete search history.

FIG. 5 is a front elevational view thereof;

(56) **References Cited**

FIG. 6 is a right side elevational view thereof;

U.S. PATENT DOCUMENTS

FIG. 7 is a left side elevational view thereof;

3,872,411 A * 3/1975 Watanabe et al. 310/312
3,931,388 A * 1/1976 Hafner et al. 310/344
4,124,809 A * 11/1978 Engdahl et al. 310/361

6,295,861 B1 * 10/2001 Tom et al. 73/24.06

FIG. 8 is a bottom plan view thereof;

FIG. 10 is a rear elevational view thereof where the cover is open;

FIG. 11 is a front elevational view thereof where the cover is open;

FIG. 12 is a right side view thereof where the cover is open;

FIG. 13 is a left side elevational view thereof where the cover is open;

FIG. 14 is a bottom plan view thereof when the cover is open.
